CLAIM

The ornamental design for a camera mount, as shown and described.

DESCRIPTION

FIG. 1 is an enlarged top, front, and left side perspective view of a camera mount, showing our new design;

FIG. 2 is a top, front, and left side perspective view of a camera mount, wherein the broken line portions are shown to illustrate environment only and form no part of the claimed design;

FIG. 3 is a top, front, and left side perspective view of a camera mount, wherein the broken line portions are shown to illustrate an alternative environment and form no part of the claimed design;

FIG. 4 is an enlarged top plan view of the camera mount shown in FIG. 1;

FIG. 5 is an enlarged front elevational view of the camera mount shown in FIG. 1; and,

FIG. 6 is an enlarged left side elevational view of the camera mount shown in FIG. 1.

The broken lines showing in FIGS. 1-6 are for illustrative purposes only and form no part of the claimed design.

1 Claim, 2 Drawing Sheets
